AUTOMATIC SAFETY PILOT

Robert E. Newell, Irwin, Pa.

Application December 11, 1945, Serial No. 634,275

10 Claims. (Cl. 158—117.1)

1

This invention relates to flame responsive cut-off valves for automatically closing a main gas supply to a heating burner, and also to a pilot burner, in the event that said pilot burner is extinguished, the operation being termed "a one hundred per cent cut-off."

The particular type of device herein described is generally referred to in the art as a "push-button safety pilot," in which the main cut-off valve is manually pushed open and is latched, or otherwise held open, by a thermally operated mechanism responsive to a pilot flame.

In controls of this character the valve may be held open at a point giving large capacity, and closed with a relatively strong spring, so are preferable for large water heaters, furnaces, ovens, etc. However valves of this type have been characterized by certain disadvantages, to overcome which it is the purpose of this invention:

First, to provide such a valve in a rugged design, with no external operating parts susceptible to damage.

Second, to insure a quick and positive operation to hold the valve open when the pilot is lighted, and to close the valve almost immediately when the pilot is extinguished, regardless of ambient temperatures.

Third, to provide such a valve, having a mechanically operated thermal element, with a wide and powerful closing movement, without imposing friction, load or strain on its thermal element while the thermal element is heated by the pilot flame.

Fourth, to provide manually operated valve opening means which is self returning to normal position while the valve is latched in open position, whereby the automatic closing of the valve will not be hindered or prevented by friction of sliding or bending parts in the manually operated valve opening means.

Fifth, to provide an automatic safety pilot having a mechanically operated thermal element installed adjacent to a main burner, with an independent pilot gas supply, and means for closing same automatically and simultaneously with the closing of the main gas supply.

Sixth, to provide a manually operative unit for a "one hundred per cent cut-off," with means permitting opening of the pilot supply line first, without opening the gas supply to the main burner, and to hold said pilot supply open automatically while the pilot is being lighted and the thermal element is being heated, prior to opening of the main gas supply.

Seventh, to provide for the operation of said 55 18, Figure 1, represents an operating arm, rig-

2

control, a rod-and-tube type thermal element having an internal rod adapted to move laterally instead of endwise, by thermal expansion of the tube, and means permitting an external adjustment of the internal rod by rotation of the tube.

Referring to the drawings:

Fig. 1 is a section view of the entire control.

Fig. 2 is a section on the line X—X, Fig. 1.

Fig. 3 is an external side view of the thermal 10 tube and pilot burner.

Fig. 4 is an external view of the outer end of the push button assembly.

Fig. 5 is a section of the middle portion of the control, with the valve parts in a different position 15 from that indicated in Fig. 1.

The main body of the control is indicated in Fig. 1 by the numeral 1. The valve closure member 2 is urged toward its closed position on valve seat 3 by spring 4. 5 is a screw cap, conveniently 20 removable for access to the valve parts within the body 1.

The body 1 is provided with a main gas passage through a chamber 6 that has an inlet 6a, and through a chamber 7 that has an outlet 8. Both 25 inlet and outlet are threaded for connections to other controls and to a main heating burner, not shown.

9 is a detachable "push button assembly" or 30 manual operating unit, adapting the control to operate as a one hundred per cent cut-off. It is attached to the control by means of a flange 10, secured by screws 11, which are threaded into a boss 12, extending from the control body 1. Between the flange 10 and boss 12 a diaphragm 13 35 is inserted for a gas seal, and also as a second valve closure member.

Pilot burner 14 is provided with ports 15 (as shown in Figs. 2 and 3), adapted to propagate a continuous flame or series of flames 16 which 40 impinge upon one side only of thermal tube 17, as indicated in Figures 1 and 2.

Figure 2 illustrates how the flame 16 encircles and heats approximately half of the circumference of the tube 17, the opposite side of the tube 45 receiving heat only by conduction. The tube is made of a chromium-nickel alloy having a low heat conductivity and therefore its opposite side is of substantially lower temperature.

This differential in temperature causes a lateral flexing action of the tube 17 in very quick response to the flame, as described in my prior application Serial No. 572,701, filed January 13, 1945, now Patent No. 2,426,786, granted September 2, 1947.

idly secured to the outer end of the tube 17, said outer end being closed gas tight. The opposite or open end of the tube 17 is screwed into a boss 19 in the body 1, the free end of the arm 18 extending through the open end of the tube into the gas outlet chamber 7. On the free end of the arm 18 a small circular cam 20 is provided by welding same on the end of arm 18, slightly off center.

A trigger 21, preferably a sheet metal stamping, is located in the outlet chamber 7, of the gas passage through body 1. The trigger 21 is pivoted at 22 in a trigger support member 23, said trigger support member being machined from a square brass bar, with a reduced round portion at each end, one end being inserted thru a central hole in the body 1 and riveted as shown at 24.

A flat spring 25 is soldered or otherwise secured at its lower end to the flat side of member 23, extending between member 23 and trigger 21, and passing through a hole 26 in trigger 21. The tension of this flat spring is to normally urge the upper end of said trigger 21 to the left, thereby causing it to engage a notch 27 in valve stem 28.

The valve stem 28 slides freely through a central hole in trigger support member 23, concentric with the axis of the control body 1.

In the process of setting the control for operation the valve closure member 2 is manually pushed open by means of the valve stem 28, which is actuated through the push button 29 in a manner later explained.

When the notch 27 in the valve stem 28 is in a position to be latched and held to open position by the trigger 21, the parts will be as shown in Fig. 1. While the pilot flame 16 remains lighted the parts will remain in this position.

However, should the pilot flame become extinguished the tube 17 will flex to its normal straight position, swinging the arm 18 in a manner causing the cam 20 to engage one arm of trigger 21, rocking the upper end of the trigger out of the notch 27, of the valve stem, as indicated by dotted lines, thus tripping the main valve to closed position.

This action will take place in a matter of six to eight seconds from the time the flame is extinguished, regardless of the ambient temperature surrounding tube 17.

As previously mentioned, the flame 16 encircles and impinges on approximately half of the circumferential surface of the tube 17. The midpoint of the flame is in a plane corresponding to the action of trigger 21, and the axis of valve push rod 28. It is in this plane that the outer end of tube 17 is flexed by the action of flame 16, said flexing of the tube, in a direction away from the flame 16, causing the free end of the arm 18, and cam 20, to move in the opposite direction, disengaging the cam 20 from trigger 21. When the flame is extinguished a reverse action takes place; the trigger is engaged by cam 20, and the valve is tripped to closed position, as above described.

The purpose of cam 20 is to obtain a convenient external adjustment of the thermal mechanism with relation to trigger 21. This is accomplished by simply rotating tube 17 in one direction or the other, which action also rotates the arm 18 and cam 20, thus changing its relation to trigger 21.

By the above described arrangement all operating parts are entirely enclosed, making it unnecessary for the comparatively delicate thermal action to be transmitted through packing pins,

etc., and obtaining a positive release of the valve with the least possible friction.

It will also be noted that since the cam 20 is out of engagement with the trigger 21 when the tube 17 is in its heated condition, there is no load whatever upon the arm 18 when the tube 17 is so heated. Much of the failure of pilot control devices heretofore, has been due to the thermal element being "loaded" when hot, for long periods of time.

It is desirable that an automatic safety pilot shut off the gas to the pilot flame as well as to the main burner, especially where the appliance on which it is used has no outside flue connection, or where "bottled" gas is used, which is highly explosive.

Heretofore this feature has been available only on "thermocouple" type pilot controls which may be installed remote from the burner on the inlet side of the main gas cock and thermostat, usually used on an appliance. In safety pilots of this type the main cut-off valve in the pilot control is used to also cut off the pilot supply gas.

However, in the present device, which must be installed adjacent to the main burner, I provide an independent pilot gas supply and a second valve operating simultaneously with the main valve, to cut off the pilot gas supply, thus making it possible to provide a one hundred per cent cut off on a pilot control having a mechanically operated thermal element, and installed adjacent the burner, on the outlet side of any thermostat or main gas cock used in the gas line, it being necessary only to connect the pilot gas supply to a point ahead of the thermostat.

I will now proceed to describe the manner in which this is accomplished.

Referring to Fig. 1, the flexible diaphragm 13 is preferably made of synthetic rubber or of thin sheet brass. It is moulded or pressed to a concavo-convex form permitting wide movement at its center. At its outer periphery it is flat, and serves as a gasket seal.

At the center of diaphragm 13 a button 31 is provided, which may be either molded in the diaphragm or be made of metal, as indicated, the purpose being to provide a flat rigid area at the center of the diaphragm to render it suitable as a valve closure member.

The body portion 30 is recessed at 32 to provide space for the movement of the diaphragm 13. At its center a valve seat 33 is formed, communicating with a central bore 34, having a flat bottom, and from which a smaller hole continues through the center of the body 30.

Slidably mounted at the outer end of the body 30 is the before-mentioned push button 29 in the form of a hollow cup, and having riveted at its center a round rod 35 which extends through into the bore 34 of the body 30.

A retracting spring 36, mounted in the body 30, normally tends to urge the push button 29 toward its outward position. The push button 29 is limited in this outward movement by a rubber collar 37, which is forced over the rod 35 and into the reduced portion 38 of the rod 35 before it is assembled and riveted to the push button 29.

A gas connection is made to the body 30 at 39 permitting gas to enter the bore 34. This gas is supplied through a line, (not shown) connected to the main gas supply at a point before any thermostat or main gas cock is used, and is supplied to the pilot burner 14, through the present control valve, independently of the main gas supply, as will now be described.

With the main valve closure member 2 and diaphragm 13 in the position shown in Fig. 1, gas passes from the bore 34 into the recess 32, from whence (see Fig. 5) it passes through small hole 40, through a registering hole 41 in the diaphragm 13, into hole 42 in the main control body 1, connecting with the pilot burner 14, which extends from the boss 19 of body 1, as shown in Fig. 3. The tapped hole in which the pilot tube 14 is inserted connects directly with hole 42, Fig. 5.

The lower end of valve stem 28, Fig. 1, has an axial bore in which is inserted a light spring 43 and a yieldable pintle 44, the pintle being held in by spinning or pressing over the end of stem 28. The purpose of this yieldable pintle 44 will presently be explained in the description of operation of the control device.

Operation

Should the pilot flame 16 be extinguished the immediate flexing of the tube 17 to its normal straight position, and the consequent movement of the free end of operating arm 18, Fig. 1, to the position shown by dotted lines, will operate the trigger 21 to trip the valve 2 to closed position.

As the valve 2 moves toward closed position the lower end of stem 28 is forced down so that the pintle 44 at the lower end of stem 28 engages the button 31 at the center of the diaphragm 13, moving the diaphragm to the position shown in dotted lines 13a, where it contacts the seat 33, thus closing the passage of pilot gas from the bore 34 to the pilot burner 14.

At this point the pintle 44 yields, slightly compressing the small spring 43, by the force of the stronger main valve closing spring 4, so that the stem 28 continues to move downward slightly, allowing the main valve closure member 2 to close completely. Thus both the main gas supply to the main burner (not shown) and the pilot gas supply is completely cut off at practically the same instant.

To relight, the operator first pushes the button 29 inwardly and turns it clockwise to the right so that pin 45, which is fixed in the body 30 enters the off-set slot 46 (Fig. 4) of the push button, where it is held by the outward pressure of the retracting spring 36 against the push button 29. The hand of the operator may then be removed from the push button 29, as it will remain in this position, at point B, Fig. 4. As a consequence of this slight inward movement of the push button the rod 35 has moved inwardly as shown in Fig. 5, so that the diaphragm is slightly lifted off the seat 33, permitting pilot gas to pass through to burner 14, in a manner already described. This slight upward movement of the diaphragm causes the pintle 44 to yield further, but, as before explained, due to the stronger spring 4 the main valve is held closed.

After the pilot is lighted, and a few seconds allowed for the thermal element to act to permit movement of the trigger 21 by the spring 25, the push button 29 is turned to the left (counter clockwise) out of the off-set slot 46 and pushed on inwardly so that the pin is in the slot at the point 47 and the push button is at position C shown in Fig. 4. With the push button 29 in this position the inner end of the rod 35 will have forced the diaphragm 13 upward, so that, looking at Fig. 1, it is in the position shown by the dotted lines 13b. This action of course forces the stem 28 and main valve disc 2 to open position where it is latched by the trigger 21.

The push button 29 may then be released, whereupon it will return to the position A shown in Figures 1 and 4, the pin 45 traveling, relatively speaking, up the slot in the push button and around to its original position. The valve and other parts will of course remain in this position as long as the pilot burner is lighted. It may be noted that the entire lighting operation may be performed with one hand.

10 It should also be noted that should the push button 29 be accidentally forced in it will be stopped by the pin 45 at position B, at which point only the pilot gas will pass to burner 14, and the main valve will not be opened. As soon as 15 such accidental pressure against the push button 29 is released it will return to its outermost position A and the pilot gas will again be cut off as before explained.

It will be noted that the main valve is easily 20 removed for cleaning; also the stem 28.

The stem 28 is a loose fit in trigger support 23 so there is no possibility of its sticking.

The trigger support 23 together with the trigger, 21, may be easily inserted through the opening 25 of the main valve, in assembling.

Neither the stem 28 nor the rod 35 are tied in with the diaphragm, but engage it freely, without binding.

30 The valve seat 33 is made easily accessible by removing the screws 11 and the body 30.

The rubber collar 37, seating at the bottom of bore 34 insures a perfectly gas tight closure, regardless of the fit of the rod 35 in the body 30.

I claim:

35 1. A safety pilot control for gas including a body portion having a main gas passage comprising two chambers therein that respectively have inlet and outlet openings, a valve seat with an opening therethrough positioned between the 40 chambers, a valve closure member co-operating with said seat, a spring normally urging said valve closure member to closed position, a push rod engaging said valve closure member, manually operated means for actuating said push rod 45 to open said valve closure member against the action of said spring, a latch-supporting member within said gas passage and rigidly secured to said body, said latch-supporting member having a guide hole for said push rod, a trigger pivoted on the latch-supporting member, said trigger being adapted to hold and release said push rod to thereby hold said valve closure member open or to release it for movement to closed position, said body being provided with an opening adjacent 50 said trigger, a hollow thermal member extending from the body in line with said opening and communicating with the opening, said hollow member being closed at its outer end, an operating arm within said hollow thermal member having one end secured to the outer or closed end of said hollow thermal member and its opposite or free end positioned to engage said trigger, and a pilot burner secured to said body in fixed relation to said hollow thermal member and provided with 55 ports adapted to propagate a flame to heat one side only of said hollow thermal member, causing said member to flex laterally at its outer end, and to thereby actuate said operating arm and trigger in a plane corresponding to said flexing 60 action.

2. A flame responsive control for gaseous fuels including a housing, a main gas passage through said housing, a valve seat and valve closure member in said gas passage to close off the flow of gas therethrough, a spring yieldably urging the valve-

closure member to its seat, manual means externally operated for opening said valve closure member against the spring pressure, latching mechanism within said gas passage for holding said valve closure member in open position, thermally operated means adapted to trip said latching mechanism upon the extinguishment of a pilot flame, said thermal mechanism comprising a tubular element secured to said housing and projecting therefrom, with its outer end closed and supporting an internal operating arm extending into said housing and engaging said latching mechanism, means for propagating a pilot flame in a manner to heat one side only of said tube to cause it to flex at its outer end and to actuate said internal arm in a lateral direction relative to the axis of said tube, and a latch-operating device mounted on the free end of said operating arm and adjustable radially of the tube.

3. A flame responsive control for gaseous fuels including a housing, a main gas passage through said housing, a valve seat and valve closure member in said gas passage to close off the flow of gas therethrough, a spring for moving the said member to closed position, a push rod within said housing for manually opening said valve closure member against the valve closing spring, a trigger support member rigidly secured within said housing, a trigger pivotally supported by said member, a spring adapted to rock said trigger into engagement with said push rod, to hold said push rod and said valve closure member in open position, a tubular thermally responsive element extending from said housing, adapted to be laterally flexed by the impingement upon one side thereof of a pilot flame, means propagating a pilot flame in contact with said element in a manner to directly heat one side only, to cause said element to flex in a given plane, and in a direction away from said flame, an operating arm secured at the outer end of said element and extending within the same, to a point within said housing, said operating arm being adapted to move laterally within said tubular element in one direction with the flexing of said tubular element in the presence of said pilot flame and to return to a normal position upon the extinguishment of said pilot flame, a tripping element on the end of said operating arm, within said housing, and positioned to engage said trigger, and means for adjusting said arm to shift the tripping element in a direction normal to the axis of said push rod to effect release of said rod and said valve closure member for movement to closed position as said operating arm approaches its normal position, after extinguishment of said pilot flame.

4. A safety pilot control for gas including a body portion provided with a passageway having a gas inlet and a gas outlet, a valve seat between said inlet and outlet, provided with an opening therethrough, a valve closure member on one side of said opening adapted to cooperate with said seat, a closing spring normally urging said valve closure member to closed position, a manually operable stem on the opposite side of said valve opening adapted to contact said valve closure member and to open it against the action of said spring and having a latch-engaging shoulder, a latching mechanism comprising a trigger, a trigger spring, and a support member having a central bore for said stem, means for pivotally supporting the trigger and the trigger spring on the supporting member, said latching mechanism

being of smaller diameter than the valve seat opening, whereby it may be inserted through said valve opening and secured to said valve body on the side of said valve opening opposite to said valve closure member, and a hollow thermal tube enclosed at its outer end, extending from said body, and having an internal operating arm responsive in its movement to the thermal action of said tube, said arm extending within said body on the side of said valve opening opposite to said valve closure member, and adapted to move said trigger out of engagement with said manually operable stem, against the tension of said trigger spring, when said thermal tube is in an unheated condition, and to move to permit return of said trigger, by the trigger spring, into engagement with said manually operable valve-opening stem, to latch said valve closure member in open position, when said thermal tube is in a heated condition.

5. A safety pilot control for gaseous fuels including a body provided with a main gas passage, a main valve adapted to cut off the gas passing through said body, a valve-closing spring, a manually operated stem for opening said valve against the pressure of the valve closing spring, a pivoted trigger on the body for releasably latching the valve open, a light spring normally urging said trigger into engagement with shoulder on said stem to hold said main valve in open position, the movement of said trigger being limited by its engagement with said stem, a thermal element comprising a hollow tube extending outwardly from said body, with its inner end in fixed relation to said trigger, burner port means in fixed relation to said tube and adapted to propagate a flame to heat one side of said tube only, adjacent its outer end portion, thereby causing said outwardly-extending portion to flex laterally out of alignment with its normal axis, and an operating arm secured to the said tube at a point remote from said inner end and extending back into said body, its free end being positioned to engage said trigger when said tube is cold, to hold said trigger out of engagement with said stem, the total movement of said arm, when the said tube is heated and flexed to its maximum point being substantially greater than the limited movement of the trigger, whereby said arm may disengage itself from said trigger and thus free itself of the load developed by the tension of the trigger while said tube is in its heated condition.

6. An automatic safety control for gas including a body member, a control member mounted therein, thermal mechanism for operating said control member, said thermal mechanism being responsive to the heat of a flame, and comprising a rotatably mounted tube extending from the body member in which said control member is situated, an operating arm secured to the outer end of said tube and extending lengthwise within said tube to a position adjacent said control member, cam means connected to the free end of said operating arm and operatively associated with said control member, and adapted to be adjusted relative to said control member by rotation of said tube, and a pilot burner having port means adapted to direct a heating flame in a manner to heat one side only of said tube, to cause it to flex and consequently to move the free end of said operating arm laterally within said tube, in a given plane, whereby said arm and cam means will operate said control member in accordance with the presence or absence of said heating flame.

7. A control device including a control mem-

ber, a thermally responsive mechanism, a lever between said control member and thermal mechanism for transmitting the action of said thermal mechanism to said control member, said thermal mechanism including an operating arm provided with a cam at one end to engage said lever, and secured at its opposite end to a thermal tube mounted in said control device and projecting therefrom, the tube and the arm being rotatably adjustable as a unit, whereby the adjustment of said cam relative to said lever may be varied, and means for applying heat to one side only of said thermal tube to cause it to flex in a given direction at all adjusted positions of the tube, and to actuate said arm and cam in a lateral direction relative to said tube, thereby effecting operation of said lever and said control member in response to the application or removal of heat from said thermal tube.

8. A flame responsive automatic pilot valve for cutting off the fuel supply to both a main heating burner and an independent pilot burner, including a housing provided with a passageway having a gas inlet, having a gas outlet to said main heating burner, and also having independent gas passages connecting to a pilot burner, a first valve in the main gas passage through said housing, a spring yieldably urging the valve toward closed position, a second valve in the independent gas passage connecting with said pilot burner, said valves being operatively connected, an external actuating member adapted to first open said second valve to admit gas to said pilot burner, and then to open said first valve to admit gas to said main heating burner, means responsive to the flame of said pilot burner adapted to retain said first valve in open position while said pilot flame is burning, and to release said valve when the pilot flame is extinguished, and yieldable connecting means between the first and second valve for closing the second valve during the movement of the first valve toward its closed position, the said first valve closing immediately after said second valve has become closed.

9. A flame responsive automatic gas cut off control adapted to cut off the fuel supply to both a main heating burner and a pilot burner, including a housing having a main gas passage and a pilot gas passage, a gas seal dividing said passages one from the other, a main valve in the main gas passage, a main valve closing spring, thermal operated means responsive to the heat of

a pilot flame adapted to hold said main valve open or release it for closing, a second valve in the pilot gas passage, means operatively connecting said main valve with said second valve, and operating through said gas seal to effect closing of said second valve by the closing action of said main valve, manual means, externally operated, for opening said second valve to admit gas to said pilot passage only, and means effective upon further movement of said manual means to open said main valve and thus supply gas to a main burner.

10. A flame responsive control for gaseous fuels including a housing, a main gas passage through said housing, a valve seat and valve closure member in said gas passage to cut off the flow of gas through said passage, a spring urging the closure member to its seat, a push rod supported at one end on said valve closure member, a manually operable member engageable with said rod, to force said valve closure member to open position by manual movement of the manually-operable member in one direction, a pilot burner adapted to propagate a pilot flame, thermal means responsive to said flame, latching means operated by said thermal means and adapted to hold said push rod and valve closure member in open position while said pilot flame is burning and to release said push rod to permit automatic return of said valve closure member to closed position, when said pilot flame is extinguished, and a retracting spring acting upon said operating member to immediately return it to its former position upon release thereof by the operator, after the valve closure member has become latched in open position, whereby the said operating member will not impede the return of said valve closure member to closed position upon release of the latching means.
